UNITED STATES PATENT OFFICE.

JAKOB GUNTHER, OF BERGISCH-GLADBACH, GERMANY.

INTERNAL-COMBUSTION ENGINE.

1,203,110.

Specification of Letters Patent.

Patented Oct. 31, 1916.

Application filed February 28, 1912. Serial No. 680,514.

To all whom it may concern:

Be it known that I, JAKOB GUNTHER, a subject of the German Emperor, residing at Bergisch-Gladbach, Germany, have invented 5 new and useful Improvements in Internal-Combustion Engines, of which the following is a specification.

This invention relates to internal combustion engines in which a combustible charge 10 is mixed in a separate combustion chamber communicating with the cylinder and into which is injected a combustible fluid. It has been proposed at the end of the compression stroke to cause a plunger connected with the 15 working piston to enter, with a certain amount of clearance, a reduced passage or neck connecting the cylinder with the combustion chamber, so that a stream of highly compressed air is forced into the combustion 20 chamber as the cylinder compression space is reduced in capacity. In engines of this type the combustible fluid has hitherto been introduced at the neck so that it might be carried along by the said compressed air 25 stream into the combustion chamber. With this arrangement, however, owing to the fact that the combustible fluid was introduced at one point only on the circumference of the prismatically formed stream of air, the 30 combustible fluid was not properly atomized and mixed with the air. This objection was partly overcome by providing a number of points of injection which, however, resulted in increasing the cost of construction, while 35 the consumption of combustible fuel was also relatively increased. According to the present invention, in engines of the type referred to these objections are avoided and a thorough atomizing and mixing of the combustible 40 fluid with the air is obtained, by a simple improvement in construction.

The chief feature of the present invention is that the combustible fluid is sprayed or injected into, approximately the center of 45 and in a direction opposed to that of, the annular or cone-shaped stream of air flowing out of the aforesaid neck connecting the working cylinder with the combustion chamber. Thorough atomizing and mixing 50 of the combustible fluid with the air is obtained owing to the facts that the combustible fluid is injected into the very center of a strong vortex of air which is set up by the highly compressed air as it flows out of the neck into the combustion chamber, that 55 the combustible fluid rebounds from the nose

of the plunger on the piston and is broken up into a fine mist by the hollow vortex of air. By means of this arrangement not only is the running of the engine improved, but 60 also the consumption of combustible fluid is about 20%-25% less than in earlier engines of this type. Further, arranging the fluid injecting nozzle in the rear wall of the combustion chamber gives a very simple construction compared with that entailed by the 65 location of the injecting devices in the sides of the combustion chamber, more especially in view of the fact that hitherto an opening in the rear wall of the combustion chamber 70 in the direction of the axis of the engine has been necessary in order to obtain access to the interior of the combustion chamber. Further, in comparison with the arrangement in which the admission of the combustible fluid takes place into the neck itself, a 75 better and more evenly distributed cooling of the cylinder head is obtained since the water space is not broken up near the cylinder by supports which may easily bring 80 about deformation of the neck and thus destroy the intended effect.

Figures 1 and 2 on the drawing are sectional views of an engine embodying different forms of my invention.

Fig. 1 of the accompanying drawing illustrates by way of example, one mode of carrying this invention into effect. Referring to Fig. 1 the working piston *a* is provided with a cone shaped surface *b* having a prismatic, here shown as a cylindrical extension *d*. The cone shaped wall *c* of the cylinder head is connected to the combustion chamber *k* by a cylindrical neck *e* within which the extension or plunger *d* loosely fits so as 90 to allow of a clearance space *f*. The injector nozzle *g* for the combustible fluid is inserted as nearly central as possible in the rear wall of the cylinder head.

The injection of the combustible fluid 100 takes place in the following manner: On the compression stroke the working piston compresses the air into the combustion chamber *k*. Before the compression stroke is completed, the plunger *d* enters the neck *e* and cuts off, to a certain extent depending upon the width of the clearance space *f*, the cone shaped annular space formed by the wall *b* and the wall *c*, from the chamber *k*. As the piston and plunger continue to advance the 105 degree of compression will be increased causing the air to pass in a powerful stream

into the chamber *k* and to rebound from the rear wall thereof thus producing violent eddies. At the same time, that is to say at about the dead center, the combustible fluid 5 is injected through the pipe or nozzle *g* into the chamber *k* and passing through the center of the vortex of air rebounds from the face of the plunger, is finely divided by the eddies and becomes thoroughly mixed with 10 the air. By a suitable choice of proportions the mixture will ignite automatically so that in such cases special ignition devices can be dispensed with.

Fig. 2 illustrates another mode of carrying the invention into effect in which the neck *e* is reduced by a further neck *v* so that the stream of air as it issues takes the form of a cone or truncated cone converging toward the rear wall of the combustion chamber. 20

The injecting nozzle for the combustible fluid must be so proportioned that the fuel can pass within the hollow cone or the hollow prism and strike the face of the plunger 25 and subject to these conditions the nozzle may have one of several outlets as in Fig. 1.

What I claim and desire to protect by Letters Patent is:—

1. In an internal combustion engine, 30 means for mixing and atomizing the fuel in the combustion chamber comprising, a nozzle for admitting fuel under pressure, means whereby part of the air in the combustion chamber may be more highly compressed 35 than the remainder, and means for directing a stream of the highly compressed air against the incoming fuel stream, whereby thorough atomization is effected.

2. In an internal combustion engine, having a combustion chamber separate from the cylinder, a passageway connecting said chamber and cylinder, means for partially closing said passageway when the piston approaches the head end of the cylinder, whereby 45 on further movement of the piston the air in the cylinder is more highly compressed than the air in the combustion chamber and a stream of air rushes through said passageway into said chamber, and a nozzle in said 50 chamber directly opposite said passageway for injecting fuel against and into the incoming stream of air.

3. In an internal combustion engine the combination of a working cylinder, a piston

therein, a separate combustion chamber in 55 the cylinder head, an axial passage interconnecting said cylinder and combustion chamber, a nozzle in said chamber directly opposite said passage for admitting the fuel under pressure, and a projection on the piston head smaller in area than said passage, 60 adapted to enter the passage as the piston approaches its head end dead center position, whereby a hollow cylindrical stream of air is driven against the fuel stream to cause 65 thorough atomization of the latter.

4. In a four stroke cycle internal combustion engine, a working cylinder, a piston therein, a combustion chamber in the cylinder head, an air inlet valve in said chamber, 70 an exhaust valve in said chamber, a cylindrical passage connecting said chamber and cylinder, a projection on the piston head of smaller diameter than said passage adapted to enter said passage as the piston approaches 75 its head end dead center position whereby a hollow cylindrical stream of air is injected into the combustion chamber, and a fuel inlet directly opposed to said passage adapted to inject fuel under pressure into said chamber 80 against the incoming air stream.

5. In combination, a cylinder, a head for the cylinder having a combustion chamber therein and in the plane of the cylinder, a piston to operate in said cylinder and having 85 a frusto-conical head, said cylinder head being correspondingly depressed to receive the head of said piston and having a reduced passage communicating said cylinder and combustion chamber, a projection of the extremity of said conical piston head adapted 90 to extend into said passage at the finish of the upward stroke of the piston and being of a lesser diameter than said passage, a fuel inlet in the center of the combustion chamber 95 and arranged to admit a stream of fuel into said chamber in direct alinement with the said projection, the walls of said passage being converged so as to direct a hollow pencil of air into the fuel inlet upon the finish 100 of the upward stroke of the piston.

In testimony whereof I have signed my name to this specification in the presence of two subscribing witnesses.

JAKOB GUNTHER.
